POST BINDER

John Schade, Holyoke, Mass., assignor to National Blank Book Company, Holyoke, Mass., a corporation of Massachusetts

Application August 29, 1939, Serial No. 292,395

4 Claims. (Cl. 129—12)

This invention relates to an improvement in loose leaf binders known as post binders. My object is to improve this type of binder with respect to its inclusion of automatic mechanism 5 for fastening its removable cover to the posts. In such structures the cover is automatically fastened when the two covers are assembled with the contents between them. Illustrations of prior art binders having this automatic feature are seen 10 in Patent No. 1,453,066 of April 24, 1923, and Patent No. 1,471,759 of October 23, 1923.

In the accompanying drawing I will disclose my improved means by which a new and useful post binder with advantages to both the manufacturer and user is attained.

In the drawing:

Fig. 1 is a top view of the assembled post binder;

Fig. 1A is a sectional view on line A—A of Fig. 20 1, the scale being about double the size of an actual binder construction;

Fig. 2 is an end view of Fig. 1;

Fig. 3 is a top view of the upper binder tube of Fig. 1 before the automatic mechanism has 25 been inserted in it;

Fig. 4 is an end view of Fig. 3, but with a portion of the cover connected;

Fig. 5 is a top view of the automatic mechanism;

Fig. 6 is an exploded view of the automatic mechanism in side elevation as compared to Fig. 5;

Fig. 7 is a top view of the saddle plate of Fig. 6; and

Fig. 8 is a sectional view on line 8—8 of Fig. 1.

The back cover portion 3' preferably includes the hinged strip 1 in the form of a flattened metal tube, but such strip may be solid. On this strip 1 the usual posts 2 are provided.

The top cover portion 3 has a similar binder strip hinged thereto and in the form of a somewhat flattened tube, referred to as a binder tube 4. In this binder tube 4, holes 5 are punched so that the tube 4 may be impaled upon posts 2 in 45 such manner that the latter may glide freely through the holes. The construction up to this point is a common one.

The new features will now be specifically disclosed in my preferred form. In the top wall of 50 this tube 4 I punch finger openings 6, in this instance of generally rectangular shape, about the size of a finger print, one such opening being located adjacent to each post hole 5. The sides of openings 6 may have small flanges 21 extending downwards, enabling tube 4 to be made of

thin material. In addition to openings 6, I punch small slot-like openings 7, one in the bottom of the tube 4 below each opening 6, as seen in Fig. 3.

I refer now to Figs. 5, 6, and 7, and the parts there shown which are to be put in the binder tube 4. I provide a lever arm or a latch plate, indicated as a whole by reference 8, one end of which forms finger piece 11. This piece is offset from the other parts by a ledge 12. The outermost portion 15 from ledge 12 is provided with a 10 post hole 13 and forms a fastening plate 15. Intermediate the ledge 12 and hole 13 I provide two open-ended slots 14, one on each side, and the plate 15 is bent slightly downwards along the line of these slots, so that plate part 15 is in a 15 canted position, as indicated in Fig. 6, when the finger piece 11 is in horizontal position. The element 9, seen in Fig. 6, is a V-shaped spring plate having substantially the width of part 8. The bottom portion of spring element 9 is provided with two small prongs 16, one at each corner. Element 10 is a saddle plate which has at one end a prong 17 extending downwards, see Figs. 6 and 7. The other end is bent upwards to form a guard 18, and at the top of guard 18 there 20 are two small prongs 19, one at each side. At 25 there are two open-ended slots in the sides of saddle 10.

By considering Fig. 6 and Fig. 1A it will be seen that parts 8, 9, and 10 can be assembled by prongs 30 16 of spring 9 being inserted in slots 20 of saddle 10, the bent portion of spring 9 resting against guard 18, and latch plate 8 being placed so that finger piece 11 rests on the top portion of spring 9 and open-ended slots 14 fit over prongs 19 of 35 saddle guard 18, the portion of saddle guard 18 between prongs 19 providing pivot means on which latch arm 8 may rock.

One feature of the invention is that the mechanism of Figs. 5, 6, and 7 may be thus assembled, either outside top binder tube 4 or through either opening 6, on the inner bottom surface of tube 4, and can be pushed into operative position in the top binder tube 4 by sliding such mechanism through either opening 6 adjacent to a post hole 5 so that the fastening plate 15 extends close to and along the under side of the tube portion between opening 6 and post hole 5 and overlaps the latter, the opening 13 in fastening plate 15 coinciding with post hole 5 of tube 4, and ledge 50 12 of latch plate 8 resting against that edge of opening 6 adjacent to post hole 5. Flanges 21 prevent finger pieces 11 when in depressed position from sliding underneath the top surface of tube 4. Prong 17 of saddle 10 will lie in slot- 55

like opening 7 in the bottom of tube 4, holding the saddle plate in position on the inner bottom surface of the tube. Action of spring 9 will hold finger piece 11 of latch arm 8 substantially flush with the upper surface of tube 4 and will also hold fastening plate 15 of the latch arm in its normally canted position, as in Fig. 1A. Both finger pieces 11, as seen in Fig. 2, are a little higher than I prefer them in the actual structure, being raised a little in that figure so they will be seen more easily. The mechanism may be removed by forcing prong 17 of saddle plate 10 out of the slot-like opening 7 where it is normally held by action of spring 9, and sliding the parts out again.

It will be understood that the assembly and insertion of one set of parts as I have described in connection with one opening adjacent to a post hole are duplicated with another set of parts in connection with the other opening. When the operations are thus completed, the top binder tube 4 with its hinged cover 3 may be impaled upon the posts 2 and the mechanism will operate automatically to fasten the cover in any position on posts 2 to which the cover is pressed, as seen in Fig. 2. This position of course depends on the contents of the loose leaf book from time to time. Finger pressure on finger pieces 11 is not necessary in the placing of the cover, since the downward movement of fastening plates 15 on posts 2 tends to raise plates 15 to a plane which will permit posts 2 to slide freely therethrough. The normal canted position of fastening plates 15 actuated by their springs (see Fig. 1A), grips the posts and any tendency to separate said plates from the posts, as by lifting binder tube 4, without pressing down on finger pieces 11, serves only to increase the grip of each fastening plate 15.

In order to detach tube 4 and cover 3 from posts 2, finger pieces 11 are depressed with the thumbs, thus pivoting latch plate 8 on saddle guard 18 or on the under side of the top surface of binder tube 4, and raising the fastening plates 15 to a plane allowing the posts to glide freely therethrough, and the cover is lifted off with the fingers.

The mechanism in the binder combination has the advantage that all the parts of Fig. 6 can be made without regard to the size of and separate from the other parts of the binder manufacture, and they can then be assembled without tools in any binder sizes as if the latter were all of one size, provided only the posts are of one diameter.

There is also an advantage in that all sizes of binders can be made without regard to operations for the assembly work of getting the automatic mechanical parts fastened. The binder tubes may be made of single sheets of metal as in Fig. 3 and with integral portions bent over to close the otherwise open ends, as in Fig. 4. The openings such as 5, 6, and 7 can of course be made most economically as the tube is subjected to its sheet metal forming operations. The openings 6 may be placed on the inside or outside of the post holes 5. Usually the openings 6 are on the outside of the post holes, but where it is thought desirable for any reason, such as the size of the binder, to have the posts close to the ends of the binder tube, the openings 6 may be made on the inside and the distance of the posts from the end of the binder tube can then be as small as may be desired.

These various advantages and others afford the manufacturer savings in time, material, labor,

and the cost of inventory. Savings also extend to the customer or user since the books may have their wearing parts replaced from the factory of the manufacturer and assembly made very easily in the field.

The user has a binder cover of very simple appearance with no protruding parts due to the automatic fastening means. The user can be supplied with a better binder at lower cost, and one more easily maintained in service for a longer time than the prior art binder of this type, so far as I know.

I claim:

1. In a post binder a binder tube having a post hole, an opening about the size of a finger print adjacent said hole in combination with mechanism to latch said tube to a post passing through said hole, said mechanism comprising a lever plate with a finger portion made to loosely fill said opening, a ledge portion made to lie along one edge of said opening, a latch portion offset from the finger portion beyond said ledge portion and made to underlie the inner surface of the top wall of said tube and extend in canted position to overlap said post hole and within the tube, a post hole in the latch portion, supporting and positioning means for said latch plate including a spring to yieldingly hold said lever plate within the tube with the finger portion substantially flush and in said opening and its latch portion in canted position, whereby a binder post may slide through said post hole in one direction and cam the lever plate out of canted position against said spring as the post passes through the post hole of said latch portion, but be latched against movement in the other direction by the tendency of said spring, aided by the movement of the post, to hold the latch in canted position, said mechanism being made in parts, assembled and pushed into said tube through said finger openings to be merely sprung in position within the tube and then held therein by spring pressure.

2. In post binder construction a top cover, a hinged binder tube thereon made of sheet metal closed at the ends, said tube having two post holes passing therethrough and two openings each about the size of a finger print, one adjacent each post hole, and two independent sets of spring pressed latch mechanisms, each comprising a spring saddle portion, a lever plate and a spring, these parts being loosely assembled together with cooperating means thereon to predetermine their relative positions and adapted to be assembled through either one of said two openings and pushed inside said binder tube to final position, said saddle member having positioning means to cooperate with said binder tube and hold the parts spring pressed in post latching position, said lever plate having a fastening portion with a post hole therein adapted to latch on a post by being canted by said spring and to be unlatched by finger pressure on one end of the lever plate, said one end lying substantially flush with and filling the opening through which the assembly was made.

3. A post binder comprising back and front covers each having a binding strip hinged thereto, two posts mounted in the back cover strip and two post holes provided in the front cover strip, the latter strip being in the form of a sheet metal binder tube having adjacent each one of its post holes an opening to the interior of the tube, about the size of a finger print, a lever plate having a post hole near one end and at the other

end a finger operating portion to loosely fit either of said openings, said lever plate being adapted to cramp its post hole end against a post when canted in one direction, and parts including a 5 spring adapted to be loosely assembled with said lever plate so as to be readily sprung into the binder tube as a whole through said finger openings and housed thereby in operating position so as to act as a spring latch for the adjacent post, 10 said plate and parts all being separable but operable as a complete spring and finger operable latch mechanism when sprung into said binder tube, such mechanism being duplicated and one provided for each of the two posts of the binder. 15

4. In post binder construction, a top cover, a hinged binder tube thereon made of sheet metal closed at the ends, said tube having post holes passing therethrough and openings each about the size of a finger print adjacent each post hole, 20 and independent sets of spring pressed latch mechanisms each comprising a spring saddle por-

tion, a lever plate and a spring, these parts being loosely assembled together with cooperating means thereon to predetermine their relative positions and adapted to be assembled through one of said openings and pushed inside said binder tube to final position, said saddle member being fixed in position on the inner bottom surface of the tube and having an upstanding portion on which the lever plate is pivoted, the pivoting point being closely adjacent the upper wall 10 of said tube, and said spring being positioned between the saddle member and the lever plate to hold the lever plate in post latching position, said lever plate having a fastening portion with a post hole therein adapted to latch on a post by being 15 canted by said spring and to be unlatched by finger pressure on one end of the lever plate, said one end lying substantially flush with and filling the opening through which assembly was made. 20

JOHN SCHADE.
